(57) **CLAIM**

The ornamental design for an umbrella handle, as shown and described.

DESCRIPTION

FIG. 1 is a front and side perspective view of one embodiment of our design for a umbrella handle;

FIG. 2 is a side view thereof;

FIG. 3 is a front view thereof;

FIG. 4 is a side view thereof, opposite the side view shown in FIG. 2;

FIG. 5 is a rear view thereof;

FIG. 6 is a bottom view thereof; and,

FIG. 7 is top view thereof.

The dash-dot-dash broken lines define the bounds of the claimed design and form no part thereof.
